UNITED STATES PATENT OFFICE.

JOHN W. ORROCK, OF MONTREAL, QUEBEC, CANADA.

SMOKE-JACK FOR LOCOMOTIVE-ENGINE HOUSES OR THE LIKE.

1,150,878.

Specification of Letters Patent. Patented Aug. 24, 1915.

Application filed October 15, 1914. Serial No. 866,856.

To all whom it may concern:

Be it known that I, JOHN W. ORROCK, of the city of Montreal, district of Montreal, in the Province of Quebec, Dominion of Canada, have invented certain new and useful Improvements in Smoke-Jacks for Locomotive-Engine Houses or the like; and I do hereby declare that the following is a full, clear, and exact description of the same.

10 My invention primarily is to produce a strong solid wooden smoke stack for use in engine houses to conduct away the smoke that issues from the locomotives, that will have no ironwork of any kind exposed to 15 the smoke fumes, and will be self-supporting without using rods, bands, bolts, wires and the like, such as are commonly used to support and keep together the present-day types of smoke stacks. This is accomplished 20 by building the walls and other portions of the smoke stack in laminated form by using material that is less in width than in depth and building up layer against layer until completed, the fastenings being driven in 25 sidewise, and as each layer is set up the following piece covers the fastenings of the previous one; by this method of construction the walls are self-supporting and there is no ironwork of any kind exposed to the 30 smoke fumes. This feature is important, as it is well known the smoke from locomotives is charged with sulfuric gases that are very destructive to ironwork. In addition, the character of construction proposed renders 35 a smoke stack built of wood semi-fireproof when set up in the manner described, so that in this respect also it has a great advantage over wood smoke stacks made of dressed and matched boards, or ordinary timber, 40 that are held together and supported by rods, bands, bolts, or the like. The advantages of this type of smoke stack are simplicity of detail, easy and cheap construction, semi-fireproof qualities, and durability.

45 My invention, therefore, consists in the laminated form of construction, the method of fastening the layers together whereby the fastenings used are protected from 50 smoke fumes, the semi-fireproof nature of the structure when built, the arrangement of the top cowl with the cover supported simply by extending the four outer layers of the smoke stack without the use of brackets or other devices, a flared hood at the bottom, the end walls of which, rest and are

supported on the sloped portion of the main side walls, which extend below the level of the end walls, this flared hood allows the locomotive some latitude when spotting under the smoke stack, and at the same time prevents lateral spreading of the smoke and fumes. For full comprehension, however, of my invention reference must be had to the accompanying drawings forming a part 60 of this specification, in which similar reference characters indicate the same parts, and wherein:

Figure 1 is a section view of an engine house provided with my invention; Fig. 2 is 70 an enlarged detail side elevation of my improved smoke jack partly in section; Fig. 3 is an end elevation thereof; and Fig. 4 is a sectional view taken on line B B Fig. 3. Figs. 5 and 6 are perspective views illustrating respectively the complete jack with a portion of the cowl broken away and of the upper portion of the jack alone tilted to 75 illustrate traverse horizontal sectional view thereof.

80 A portion of the roof of an engine house is indicated at 2, the purlins for supporting the same at 3, 4 and 5 and the rails at 6. A smoke jack constructed according to my invention projects through an opening in 85 the roof between the purlins 4 and 5.

90 In order to secure the smoke jack to the roof in such a way that the use of rods, bands, bolts and the like will not be necessitated the side walls are supported on the roof boards cantalivered over purlins 4 and 5 located one on each side thereof, and trimmers 8 are located one on each side thereof and are rigidly secured to said purlins, their 95 ends being tenoned into the purlins 4 and 5. In order to avoid exposure of any ironwork to the fumes of the smoke each layer is nailed sidewise throughout its length to the side of the adjoining layer, the following layer thus covering the nails fastening the preceding layers. The portion of the smoke 100 jack above the roof is of substantially square cross-section throughout its height. Below the roof, however, the side walls are extended both ways in the direction of the track for the purpose of affording greater leeway 105 in the spotting of the locomotive. The inclined end walls are secured to the inclined edges 16 of these side walls. To prevent a draft from causing the smoke to spread laterally through the engine house the side walls of my improved jack are extended

downwardly as at 25 below the end walls, so that the stack of the locomotive would enter between these side walls and be to all intents and purposes inclosed by the flared 5 mouth.

The cowl is indicated at 30 and in order to support it without materially increasing the weight and cost of the jack I extend two of the laminæ nearest each of the four corners upwardly as at 31, secure cross pieces 10 32 thereto and fasten the cowl, which is also laminated, on the top thereof.

The connection between the jack and roof of the engine house is made more rigid and 15 secure by making the portions 35 of the roof boards contiguous to the jack constitute one of the horizontal laminæ at both front and sides. The joint is completed with fillers 36 and 37.

20. The laminated construction imparts semi-fireproof qualities to the jack and to further enhance the security against fire I treat the wood with a fire-proofing composition before erection.

25. What I claim is as follows:—

1. The combination with the roof of an engine-house, of a smoke jack carried by the roof with portions thereof above and below the same, the upper portion and two 30 opposite sides of the lower portion consisting of vertical laminæ, and the other sides or ends of the lower portion consisting of horizontal laminæ.

2. The combination with the roof of an engine-house, of a smoke jack, two of the 35 sides of the body of which consist of horizontal laminæ and a portion of the roof incorporated therein and forming a component part thereof in substitution for one of the laminæ of each of the said sides.

3. The combination with the roof of an engine-house having an opening of a smoke-jack comprising a pair of unitary vertical sides extending through the opening and 45 other portions whereof are supported by the unitary sides.

4. The combination with the roof of an engine-house, having an opening, of a smoke-

jack comprising a pair of unitary perpendicular sides extending through the opening 50 and having their lower sides downwardly expanded, the other sides being secured to and carried by the side edges of the vertical sides.

5. The combination with the roof of an 55 engine-house, having an opening, of a smoke-jack, a portion of which extends through the opening, and other portions supported by the roof, that part beneath the roof having two of its opposite sides vertical and its ends or other sides flared and carried by the perpendicular sides, the sides and ends of the said jack each consisting of a laminated member, the laminæ of which are of less width than depth, and fastened together 60 with nails completely covered by the laminæ.

6. A smoke-jack for an engine-house, the upper end of which is of rectangular cross section, and consists of vertical laminæ, the corner laminæ of which are extended upwardly and have a cowl mounted thereon. 70

7. The combination with the roof of an engine-house comprising spaced purlins, roof boards cantalivered over the purlins, a unitary smoke-jack of rectangular cross section 75 located in position partly above and partly below the roof two of the opposite side walls of the jack extending through the opening and being equal in vertical length to and forming component parts of the jack, and the portions of the other sides above the roof being supported on the roof boards and on the first mentioned side, and the portions of the said other sides below the roof being supported upon the expended portions of the said first mentioned sides and trimmers having their ends tenoned into the purlins and located one on each side of the portion of the smoke jack beneath the roof. 80

In testimony whereof I have signed my 90 name to this specification in the presence of two witnesses.

JOHN W. ORROCK.
